UNITED STATES PATENT OFFICE.

KENNETH S. MACINTIRE, OF WOOLWICH, MAINE.

DESIGN FOR A PENDANT.

Application filed January 31, 1924. Serial No. 8,498. Term of patent 14 years.

To all whom it may concern:

Be it known that I, KENNETH S. MACINTIRE, a citizen of the United States, residing at Woolwich, Sagadahoc County, Maine, have invented a new and original and ornamental Design for a Pendant, of which the following is a specification, reference being had to the accompanying drawings, forming part thereof, in which:

Figure 1 is a front elevation of the pendant showing the new design;

Figure 2 is a side elevation of the same. The said pendant or charm may be suspended from ear rings, or hung from a cord about the neck, or used in any similar manner as a decorative article of jewelry.

I claim as my invention:

The ornamental design for a pendant as shown in the accompanying drawings.

KENNETH S. MACINTIRE.
